MEANS FOR IDENTIFYING ARTICLES

Thomas F. Murphy, Wellsboro, Pa.

Application August 27, 1937, Serial No. 161,343

14 Claims. (Cl. 40—2)

This invention relates to identification means and more particularly to means adapted to be applied to articles such as those fabricated of textile material or the like, for example, articles of apparel, house furnishings, or other items of domestic economy—to indicate ownership, utility, or grade, or to distinguish such articles upon any other appropriate basis.

The general object of the invention is to provide novel and improved means of identification for articles of the type described, and a novel method of applying such means and rendering them effective for the intended purpose.

As an example of one field of usefulness of my improved identification means, may be cited the distinguishing of articles of clothing or personal apparel belonging to members of large families, pupils at boarding schools, members of athletic clubs, or residents of dormitories at institutions of various kinds. For this purpose, there are numerous expedients employed for distinctively marking such articles, these including the inscribing upon them of names, numbers or other insignia by the use of indelible inks, or by sewing or embroidering names or initials thereon. Such means are almost invariably applied to the articles by the user or by someone else under his direction, and these methods are inconvenient, time consuming, and bothersome; and, in some cases, expensive.

Therefore, as a more particular object of the present invention, there is contemplated the application of novel identification means to the article before purchase, as one step in the process of manufacture or of preparing the article for the market; and it is also proposed to provide as a feature of said identification means, certain elements which may be very easily and quickly altered by the wearer or user after the articles come into his possession, whereby distinct individual marking of his property may be effected.

In its preferred embodiment, the invention comprises the application to an article, such as an item of apparel, of a tag, label, or similar device, preferably bearing an indication of its distinguishing function and also carrying a certain grouping of separately applied markings preferably arranged in a relatively simple, pleasing pattern or design; each of said markings being readily capable of being individually and intentionally removed by the user, but not liable to be removed or obliterated during the ordinary handling, wearing, or laundering of the article. By the removal of one or more of the individual markings comprising the design, the indicia may

be altered or varied to distinguish the articles belonging to one member of the family or organization from those belonging to another who has selected one or more different markings to delete. It is also possible to eliminate all of the markings in cases where the identification function is not necessary or desired.

One very practical method of applying the marking means is by affixing separately removable loops of thread or lines of stitching to the tag or label to be applied to the garment or other article by means of any suitable textile working process, such as sewing, weaving, knitting, etc. However, the invention also contemplates the application of the identifying marking means or devices by means of such processes directly to the article itself and where a tag or label would be unsightly or inappropriate as in the case of handkerchiefs, napkins, or the like, a tag or label made of paper, cardboard, thin cloth or similar frangible material and bearing a trademark and other wording indicating the purpose and method of altering the indicating pattern, may be temporarily affixed to the article, for example, by means of the very threads which make up the marking means. Then after purchasing the article the owner may tear off the paper label and then pull out the selected marking threads.

Other objects and features of novelty of the invention will be apparent from the following specification when read in connection with the accompanying drawing in which certain embodiments of my invention are illustrated by way of example.

In the drawing:

Figure 1 is a fragmentary plan view of a shirt to which an indicating or identifying means embodying the principles of my invention has been affixed;

Figure 2 is a cross sectional view of the label 40 40 taken substantially on line 2—2 of Figure 1, and on a greatly enlarged scale;

Figures 3, 4 and 5 are fragmentary plan views of labels or tags applied to articles or materials which are to be distinguished from each other, 45 and each exhibiting a different pattern of markings, effected by the removal of one or more of such markings by the respective owners;

Figure 6 is a fragmentary plan view of a fabric article such as a handkerchief to which another 50 embodiment of the invention has been applied, in its original condition as purchased;

Figure 7 is a magnified sectional view similar to Figure 2 but taken along line 7—7 of Figure 6; and

Figures 8 and 9 are similar views showing an article such as illustrated in Figure 6, after removal of the temporary label, and with different arrangements of identifying markings thereon.

Referring more particularly to Figure 1 of the drawing, it will be seen that the article selected for exemplary illustration is a shirt indicated generally by the reference character 10. As is usual in the case of this type of merchandise a label is applied to the inside of the shirt at the rear and beneath the collar portion thereof. This label usually exhibits the brand or trademark of the article and the maker's name. The counterpart of such a label is indicated at 12 in the drawing and in addition to setting forth the brand as shown at 13, the label also contains wording which indicates the additional function of the identification means forming the subject of this invention, such as represented by the words "Hismark-Hermark", denoted by the reference numeral 14. The actual means for providing individual identification markings for the articles is shown at 15 and in this particular embodiment comprises a design or pattern made up of six separate threads represented by the reference numerals 16. These threads may be applied in any suitable way as, for example, by ordinary stitching as would be effected by a sewing machine, or by weaving or knitting but in any case applied so as to be readily removable. However, in the exemplary form illustrated in the present case, the thread markings 16 are applied as single loops of thread knotted upon the underside of the label 12 as indicated at 17 in Figures 2 and 7 of the drawing.

In order to effectively differentiate the possessions of one member of the family or organization from those of the others, the members should agree beforehand to select certain individual groupings of the markings indicated in their original arrangement at 15, and then each will pull out one or more of the threads 16 in order that the remaining threads will represent his particular identifying pattern. For example, in Figure 3 of the drawing the owner of the article represented fragmentarily at 20 has pulled out the upper horizontal thread 16 leaving the threads forming an X-shaped pattern over the bottom horizontal marking, as indicated at 15'. The owner of the article 21 represented in Figure 4 has pulled out the upper left hand thread 16 of the X-shaped design, leaving his pattern 15'; and the owner of the article 22 shown in Figure 5 has eliminated both the upper left and the lower right hand thread 16 to leave an identifying pattern 15² of substantially Z-shape. It is obvious that an exceedingly large number of different combinations of markings can be effected in this manner so as to identify articles belonging to a great number of persons. Of course, if it is found to be necessary, a larger number of threads than the six shown in the present embodiment may be initially applied to the article.

In the modification of my invention illustrated in Figures 6-9 of the drawing, there is provided means for applying an inconspicuous identifying sign to articles such as handkerchiefs, napkins, or the like in which the tag 12 would be inappropriate. In this embodiment a label 25 is employed which is preferably made of paper or some thin frangible material and may bear any insignia desired such as the trade-mark, manufacturer's name or the like, and also the designation indicated at 14 indicative of the distinguishing function of the marking means. This

label or slip 25 may be secured to the article such as the handkerchief 30 by the threads 16 which comprise the markings, as clearly shown in Figures 6 and 7 of the drawing. Then after purchasing the article the user will tear off the label 25 and the identifying pattern 15 will appear as in Figure 8. Then the owner will pull out one or more of the threads 16 to effectuate a remaining pattern which will be the distinctive marking of his possessions as, for example, the pattern indicated at 15¹ in Figure 9.

In order to aid in the quick identification of the articles and to improve the appearance of the design each of the threads 16 may be of a different color.

It will be readily understood that in the utilization of this invention in a particular field, as for instance in marking textiles or apparel subject to laundering, a design or pattern such as the one illustrated in the accompanying drawing 20 may easily become established and universally accepted in the trade, and in this manner eliminate the necessity for the consumer to make individual markings after purchase. This proposed standardization of the original pattern is also 25 highly desirable in order that the same final identifying pattern adopted by an individual user may be available to him in all of his articles of apparel such as shirts, socks, underwear, neckties, or the like, at whatever time they are purchased. 30

Of course, it will be seen that in such application to articles of apparel where, because of the nature or number of the household or family membership, no identification means is necessary, or where because of the nature of the article 35 itself, for example, in the case of a handkerchief or where the owner might not wish to have it contain the identifying thread marking, all of the threads can be obliterated without the slightest harm to the article.

It will thus be seen that by means of the present invention there has been provided means whereby articles belonging to a large number of persons residing together may be differentiated, and a very wide variety of distinguishing marks 45 provided with very little care, exertion, or inconvenience on the part of the owner.

It will be understood that various changes and modifications can be made in the embodiments illustrated and described herein without departing from the scope of the invention as defined by the following claims.

Having thus described the invention, what is claimed as new and desired to be secured by Letters Patent is:

1. Identification means for an article of the class described comprising a group of separate marking means applied to said article, said group originally comprising a distinctive design, each of said marking means being capable of ready intentional removal from the article, whereby when one or more is removed from the article the remaining marking means exhibit a different design readily distinguishable from the original.

2. Identification means for articles of the class described comprising checks, labels, tags or the like adapted to be applied to said articles, a plurality of detached marking devices separately affixed to each of said checks, labels, or tags in a regular predetermined pattern, said marking devices all being secured to said label or the like against accidental obliteration but readily removable by intention, whereby the removal of one or more of said marking devices results in the formation of different patterns easily dis-

tinguishable from the original and from each other.

3. Identification means for articles of the class described comprising threads affixed to said articles so as to form a plurality of separate visible readily removable lengths arranged to form a predetermined pattern, whereby when one or more of said lengths of thread is pulled out the patterns remaining are readily distinguishable from the original pattern and from each other.

4. Identification means for articles of the class described comprising a plurality of separate threads affixed to the article to form an original standardized pattern, each of said threads being readily removable from the articles, whereby when one or more of said threads is pulled out, the patterns remaining are readily distinguishable from the original pattern and from each other.

5. Identification means for articles of the class described comprising a plurality of different colored threads affixed to the article to form an original standardized pattern, each of said threads being readily removable from the articles, whereby when one or more of said threads is pulled out, the patterns remaining are readily distinguishable from the original pattern and from each other.

6. Identifying means for an article of the class described comprising a changeable label adapted to be applied to said article, a plurality of separate threads affixed to said label so as to form a predetermined pattern thereon, said threads being separately and readily removable from the label whereby when one or more of said threads is removed the pattern remaining is readily distinguishable from the original pattern and from similar patterns effected by the removal of other threads from similar labels applied to other articles.

7. Identifying means for an article of the class described comprising a changeable label adapted to be applied to said article, a plurality of separate threads affixed to said label so as to form a predetermined pattern thereon, said threads being separately and readily removable from the label whereby when one or more of said threads is removed the patterns remaining are readily distinguishable from the original pattern and from similar patterns effected by the removal of other threads from similar labels applied to other articles, and other means on said label indicating the function of said changeable pattern.

8. Identification means for articles of the class described comprising a label bearing an indication of the function of said identification means, a plurality of separate threads securing said label to an article, said threads being arranged to form a predetermined pattern, each of said separate threads being readily removable, whereby when one or more of said threads is pulled out, the pattern remaining is readily distinguishable from the original pattern and from patterns applied to other articles from which different threads have been removed.

9. Identification means for articles of the class described comprising a label bearing display matter, a plurality of separate threads securing said label to said article, said threads being arranged to form a predetermined pattern, each of said separate threads being readily removable, whereby when one or more of said threads is pulled out, the pattern remaining is readily distinguishable from the original pattern and from patterns

applied to other articles from which different threads have been removed, said label being composed of frangible material whereby it may be torn from the article without disturbing the threads comprising the identifying design.

10. The method of rendering articles of commerce of the class described identifiable comprising applying a series of separate and distinct marking means to said article in a predetermined pattern or design as a step in the preparation of said article for the market, and then removing from said article certain selected ones of said marking means in order to effectuate a distinctive identifying pattern of the remaining marking means.

11. The method of rendering the individual ones of a series of otherwise similar or identical articles identifiable, which comprises affixing to each article a plurality of separate threads to form an original standardized pattern, then pulling out one or more selected threads from each article so that the remaining threads in each article form a distinctive identifying pattern which is different from that of the original pattern and from each other.

12. The method of rendering the individual ones of a series of otherwise similar or identical articles identifiable, which comprises affixing to each of said articles a frangible label by means of a plurality of separate threads, the visible portions of which form an original standardized pattern, then after said label has served its purpose, tearing off the label leaving the threads in the article intact, and finally pulling out one or more selected threads from each article so that the remaining threads in each article form a distinctive identifying pattern which is different from that of the original pattern and from each other.

13. The combination of an article of commerce intended for ultimate personal use or consumption with individual identification means therefor, said means comprising a group of separate marking devices affixed to said article to form a complete distinctive design, said marking devices all being secured to said article against accidental obliteration or removal but readily removable by intention, whereby the removal of one or more of said marking devices by the user results in the formation of different patterns easily distinguishable from the original pattern and from each other.

14. The combination of an article of commerce intended for ultimate personal use or consumption with changeable individual ownership indicia therefor, said indicia comprising a group of detached marking devices separately applied to said article prior to use so as to form an original standardized pattern, said marking devices each being separately and readily removable from said article by the user, whereby when certain selected ones of said marking devices are removed, the pattern remaining is readily distinguishable from the original pattern and from similar patterns effected by the removal of other of said marking devices from other articles of the same kind belonging to other users, said devices being so affixed that they are not likely to be inadvertently removed during use, handling, cleaning, or otherwise servicing of the article.

THOMAS F. MURPHY.
